UNITED STATES PATENT OFFICE.

NATHAN WELLMAN, OF MEMPHIS, TENNESSEE.

DESIGN FOR A TOY ORNAMENT.

Application filed August 7, 1923. Serial No. 6,976. Term of patent 3½ years.

To all whom it may concern:

Be it known that I, NATHAN WELLMAN, a citizen of the United States, and a resident of Memphis, in the county of Shelby and State of Tennessee, have invented a new, original, and ornamental Design for a Toy Ornament, of which the following is a specification.

Referring more particularly to the accompanying drawing:

The figure is a side perspective view of a toy ornament showing my new design.

My invention comprehends a novel design of toy ornament more especially adapted to be attached to the front of a bicycle or the like.

I claim:

The ornamental design for a toy ornament, as shown.

NATHAN WELLMAN.
